UNITED STATES PATENT OFFICE

GEORGE NAISMITH AND DONALD M. NAISMITH, OF PITTSBURGH, PENNSYLVANIA,
ASSIGNORS TO DONALD M. NAISMITH, OF PITTSBURGH, PENNSYLVANIA

FURNACE

Application filed May 26, 1931. Serial No. 540,024.

Our invention is an improvement in heating furnaces of the regenerative type particularly adapted to the heating of ingots and the like within a soaking pit or heating chamber.

It has in view to provide a furnace construction in which the gases of combustion are supplied to one side of the soaking pit and withdrawn from the other, with circulation through the pit from side to side either in a horseshoe travel, as to all or some of the gases, or directly across from one end to the opposite end.

In our improved construction we provide means for preheating the air and gas in their passage through a regenerative chamber embodying gas circulating channels or ports, with combination of the pre-heated air and gas in a common mixing chamber leading to one side of the soaking pit; a similar corresponding construction leading from the other side of the soaking pit for the outgoing gases or products of combustion; fuel supply means supplementing such gas supply, either through the checkerwork of the regenerative chamber, or thereabove at the remote end of the mixing chamber, or both; means controlling supply of producer or like gas to the pre-heating ports extending through the regenerative chamber, means controlling supply of air thereto; means controlling withdrawal of the waste gases; and various other features of construction and advantage, as hereinafter described and claimed.

The present improvement and construction is particularly adapted to the pre-heating of the fuel supply by incorporating the circulating flues therefor with the regenerative chamber and in close association with the checkerwork thereof, thereby subjecting the flues themselves in such checkerwork to the heating action of outgoing gases with the resulting advantage of pre-heating upon reversal of the circulation for both the air and gas, with the resulting advantages of improved and accelerated combustion upon combination of both immediately upon entering the mixing chamber.

By our improved construction we are enabled to simplify the reversing valve and

damper installation to reverse the gas circulation from its entrance to the soaking pit and outlet therefrom in combination with the gas ports passing through the air regenerator, with corresponding reversal of circulation in an opposite direction across the soaking pit, utilizing a single reversing valve for both sides of the regenerating members.

These advantages are present in the preferred constructions and arrangements illustrated in the drawings, in which:

Fig. 1 is a longitudinal vertical section through the furnace on the line I—I of Fig. 2, showing the gas supply flues incorporated with the regenerator and in outgoing circulation with the stack;

Fig. 2 is a horizontal section, part plan view, on the section line II—II of Fig. 1, showing the air and gas pre-heating regenerative chambers in operative relation to one side and the other of a double hole soaking pit;

Fig. 3 is a vertical sectional view on the line III—III of Fig. 2, showing the circulation of incoming air and outgoing waste gases delivered to and withdrawn from each side of the furnace respectively;

Fig. 4 is a transverse vertical section on the line IV—IV of Fig. 2;

Fig. 5 is a similar section on the line V—V of Fig. 2;

Fig. 6 is a similar section on the line VI—VI of Fig. 2;

Fig. 7 is a part sectional view like Fig. 1 but showing the gas flues in supply circulation;

Fig. 8 is a partial similar section on the line VIII—VIII of Fig. 2;

Fig. 9 is a horizontal sectional view similar to Fig. 2, showing the construction at one side of a soaking pit of a continuously straight installation;

Fig. 10 is a similar view of the construction of the other side of the soaking pit in such installation.

In the construction shown we have illustrated two arrangements of air and gas pre-heating regenerative chambers, in one of which such chambers are arranged side by side of an intervening partition wall, one leading to one side of the soaking pit and the

other from the other side. In the alternative arrangement the regenerative chambers are located in alinement on opposite sides of the soaking pit with provision for alternating circulation therethrough and both downwardly and upwardly through the regenerative chamber and the gas supply and exhaust flues incorporated therewith.

Referring to the principal figures of the drawings, the soaking pit or heating chamber of the furnace is preferably divided into two main holes or cavities 2a and 2b of generally rectangular construction enclosed within side walls 3—3, outer end wall 4, and an inner 10 transverse partition 5. The latter forms a partial closure of the heating chamber, providing the end wall of the regenerative portions of the furnace which are also enclosed between the main side walls 3 and the opposite 15 end wall 6.

A central partition wall 7 extends vertically from the base of the construction upwardly to the roof forming a support for the arched roof coverings 8—8 of the regenerative chambers containing the checkerwork 9, and the common mixing and combustion chamber 13. Such roof arches extend longitudinally from partition 5 to end wall 6. As shown, wall 7 extends by partition wall 10 across and 20 through the middle of the two-hole soaking pit, having an arched communicating opening 11 for circulation of heating gases therethrough from one hole 2a to the other hole 2b.

The two-hole soaking pit, as thus constructed, is of ample depth for the placement of ingots of normal height, resting on the supported floor 14 carried by beams 15 or otherwise and provided with the removable cover or covers 16 mounted by wheels 17 on 25 suitable tracks or runways, following general practice.

In our improved construction we preferably utilize producer gas or other equally efficient fuel leading from a conduit or tunnel 30 18 through circulating flues 19 leading to transverse supply passages 20 arranged vertically below and communicating with a series of vertical ports 21. Such ports are arranged transversely across the width of each regenerative chamber, alternating and in close association with the checkerwork thereof, as in Figs. 2 and 6, and opening into mixing chamber 13.

The main body of checkerwork 9 extends 35 from the outer side of such gas circulating ports 21 backwardly for the full depth of the gas ports and of the chamber beyond, and of its full width, beyond the ports 21.

Below the checkerwork extends a series of 40 circulating flues 22, communicating with the main body of the checkerwork and its extensions between ports 21. Flues 22 are divided by comparatively thin supporting walls underneath the checkerwork, beyond which is 45 a widened common communicating flue 23, the

extension of which leads upwardly to the base portion of wind box 24. One such wind box is at each side of the blower or fan B and has a pipe 25 which communicates laterally with the wind box and fan B and leads upwardly within the base of outlet stack 26.

Intervening between main 18 and ports 21 of circulating main channel 19 is a cut-off damper 27 of well known commercial type, by the operation of which the gas supply to one or the other side of the heating chamber is furnished. A cross port 28 opens and closes communication between flues 19 and 23 by control of an opening and closing damper 29. By closing damper 29 gas supply is directed to ports 21 and by opening the damper, reverse circulation is opened to flue 23 and stack 26. The latter is connected by its operating stem 30 with lever mechanism 31 for operation of an opening and closing valve 32, adapted to cooperate with damper 29.

Such damper and valve are capable of being adjusted to each other, as to relative circulation clearance, so as to regulate the draft through flues 19 and 22—23 during operation. This is of importance in case checkerwork is also placed in flue 19 and ports 20 and 21, or any of them, for additional regeneration.

Supplemental fuel supply, as by blast furnace gas, is introduced by pipe or pipes 33 leading through wall 6 to the end portion of mixing chamber 13, or by pipe or pipes 34 to the chamber 35, within the body of the checkerwork. By such arrangement comparatively lean gas, such as blast furnace gas, is admitted to those portions of the installation where it will be immediately combined with highly heated air, as with the pre-heated air passing through and above the checkerwork, or by becoming associated therewith in passing upwardly through the checkerwork from such chamber 35. With either or both arrangements such gas becomes highly heated and immediately combustible, assisted by such pre-heated air supply.

Likewise, as to the main body of gas passing upwardly through ports 21, within the surrounding pre-heated checkerwork of the regenerative chamber, such gas passes from ports 21 into immediate combustible association with the highly pre-heated air, with maximum resulting heating value in the adjacent hole of the soaking pit.

The gases of combustion pass from the other side or hole of the pit, circulating downwardly through the main body of checkerwork 9 and also through the ports 21, such latter circulation passing through open port 28 and combining with the main current of waste gases from the checkerwork and outwardly through stack 26.

It will be understood that two such stacks are provided, one at each side as shown in Fig. 2 for alternating operation for intake of

air through air box 24 at one side and outward circulation to the stack at the other side.

With supply of gas from main 18 cut off by valve 27 and with damper 29 raised opening port 28 and valve 32 the outgoing products of combustion will pass downwardly through gas port 21 and checkerwork 9, pre-heating these channels in passing to and outwardly of the corresponding stack 26.

At the other side, with valve 32 and damper 29 closed, and gas supply valve 27 open, as in Fig. 7, gas will pass through ports 19, 20 and 21 to the mixing chamber 18.

Likewise, with damper 29 and valve 32 closed, air from the wind box 24 will be reversed downwardly and passes by ports 23, 22, upwardly through the checkers and combines with pre-heated gas in the mixing chamber 18. The circulation is reversed at intervals from time to time, with or without corresponding supplemental supply of fuel from pipes 33 or 34, or both.

When the soaking pit 2 is located directly between oppositely extending pre-heating and fuel supply chambers, as in a Siemens regenerative furnace of well known construction, we utilize endmost chambers, each having an independent fuel and air supply, as shown in Figs. 9 and 10.

In such case the longitudinal cavity is enclosed within side walls 3, 3, and ends walls 6, 6. The lower gas ports 19 communicate with an outer main 18 and the upper air ports 35 23 lead from a separate blower and air box combined with a single outlet stack 26 as shown, one at each outer end of the furnace, operating alternately for each reversal.

The construction and operation is otherwise the same as above described, the circulation of air and gas in combustion passing directly across and through the soaking pit 2 and then downwardly through the gas ports 21 and checker 9 to the stack, when damper 45 29 is raised.

In each case the fuel gases pass into one side of the soaking pit and out the other side, with pre-heating of the gas flues 21 embodied in the surrounding checkers of the regenerative chamber. Likewise additional fuel may be supplied to the remote end of the mixing chamber by pipes 33 and 34, as desired.

The construction and operation of the furnace will be readily understood from the foregoing description. It provides for a highly efficient and economical application and use of the fuel in its application, with maximum conservation and utilization of waste heat values.

60 What we claim is:

1. In a furnace, the combination with a soaking pit, of walls enclosing a chamber leading into one side of the soaking pit and a corresponding chamber leading from the other side thereof, a regenerator for each of

said chambers, means supplying air to one of said regenerators, enclosed fuel conducting ports leading upwardly through and between opposite portions of said regenerator for admixture with heated air at the top thereof, and means controlling supply of air and fuel to one regenerator and withdrawal of waste gases from the other.

2. In a furnace provided with a two-hole soaking pit, the combination therewith of walls enclosing a chamber leading into one hole and a corresponding chamber leading into the other hole, means embodying air heating checkerwork and a series of closed gas heating flues extending bodily through the checkerwork for supplying heating fuel through said chamber to one of said holes, and means embodying similar checkerwork and flues for exhausting waste gases through said chamber from the other hole.

3. In a furnace provided with a two-hole soaking pit, the combination therewith of walls enclosing a chamber leading into one hole and a corresponding chamber leading into the other hole, means embodying air heating checkerwork and a series of closed gas heating flues extending bodily through the checkerwork for supplying heating fuel through said chamber to one of said holes, means embodying similar checkerwork and flues for exhausting waste gases through said chamber from the other hole, and means for supplying additional fuel to the chamber above the checkerwork.

4. In a furnace provided with a two-hole soaking pit, the combination therewith of walls enclosing a chamber leading into one hole and a corresponding chamber leading into the other hole, means embodying air heating checkerwork and a series of closed gas heating flues extending bodily through the checkerwork for supplying heating fuel through said chamber to one of said holes, means embodying similar checkerwork and flues for exhausting waste gases through said chamber from the other hole, and means for supplying additional fuel to the checkerwork for circulation therethrough to said chamber.

5. In a furnace, the combination with a soaking pit, of walls enclosing a chamber leading into one side of the soaking pit and a corresponding chamber leading from the other side thereof, a regenerator for each of said chambers, a conduit supplying air and a conduit supplying gas at times to each one of said regenerators, said conduits having a communicating port therebetween, an outlet stack in communication with the air conduit having an opening and closing valve, and a damper for the communicating port cooperating and connected with the valve adapted to control circulation of outgoing gases at other times to the stack.

6. In a furnace, the combination with a

soaking pit, of walls enclosing a chamber leading into one side of the soaking pit and a corresponding chamber leading from the other side thereof, a regenerator for each of said chambers, a conduit supplying air and a conduit supplying gas to each one of said regenerators having a communicating port, an outlet stack in communication with the air conduit of each chamber having an opening and closing valve, a damper co-operating therewith adapted when open to provide for circulation of outgoing gases from both conduits and through said port to the stack, and means supplying air through the base of each stack for inward circulation through the air conduit and checkerwork of each of said chambers.

7. In a furnace, the combination with a soaking pit, of walls enclosing a chamber leading into one side of the soaking pit and a corresponding chamber leading from the other side thereof, a regenerator for each of said chambers, means including a flue supplying air at times to one of said regenerators, an outlet stack in communication therewith having an opening and closing valve, a fuel supply conduit, and a damper-controlled opening between the air supply flue and the fuel supply conduit adapted to provide circulation of outgoing gases from said flue and conduit at other times to the stack.

8. In a furnace, the combination with a soaking pit, of walls enclosing a chamber leading into one side of the soaking pit and a corresponding chamber leading from the other side thereof, a regenerator for each of said chambers, an air supply conduit and a separate adjacent fuel supply conduit directing air and fuel respectively upwardly through and between opposite portions of one regenerator respectively and a similar pair of conduits for the other regenerator, said pairs of conduits operating alternately for reverse outward circulation, a single outlet stack for each pair of conduits, and a damper controlled port connecting each pair of conduits adapting them to operate independently for air and fuel supply or together for exhaust to the stack.

9. In a furnace, the combination with a soaking pit, of walls enclosing a chamber leading into one side of the soaking pit and a corresponding chamber leading from the other side thereof, a regenerator for each of said chambers, an air supply conduit and a separate adjacent and parallel fuel supply conduit directing air and fuel respectively upwardly through and between opposite portions of one regenerator respectively and a similar pair of conduits for the other regenerator, said pairs of conduits operating alternately for reverse outward circulation, a single outlet stack for each pair of conduits provided with an opening and closing valve, a port connecting each pair of conduits, and

a damper therefor operatively connected with the stack valve.

10. A reversible heating furnace having a heating chamber and a single regenerative chamber provided with an upper mixing and combustion cavity opening into the heating chamber and independent air and gas supply passages both extending bodily through and within the lateral area of the regenerative chamber for pre-heating and mixing and combustion in the upper cavity.

11. A reversible heating furnace having a heating chamber and a single regenerative chamber provided with an upper mixing and combustion cavity opening into the heating chamber and independent air and gas supply passages both extending bodily through the regenerative chamber for pre-heating and mixing and combustion in the upper cavity, and circulation and control means including a damper-controlled communicating port between the air and gas supply passages whereby the regenerator on reversal serves as an outlet conductor for waste gases.

12. A furnace having a pair of main end-most heating chambers, a middle vertical wall with a circulation opening in its outer portion connecting the heating chambers, outer vertical end walls for the heating chambers, a lower air pre-heating chamber at each opposite side of said middle wall, a side-by-side pair of common mixing, combustion and delivery conduits each communicating with one of said pre-heating chambers and with one of the main heating chambers at each side of said middle wall, said conduits extending continuously from the main heating chambers to opposite inner end walls of the pre-heating chambers, means for supplying an upward circulation of air through the pre-heating chamber at one side of the middle wall and for exhaust circulation through and from the heating chamber at the other side of said wall, and means for introducing fuel through the inner end wall of each common mixing, combustion and delivery conduit above the air pre-heating chamber.

13. A furnace having a pair of main end-most heating chambers, a middle vertical wall with a circulation opening in its outer portion connecting the heating chambers, outer vertical end walls for the heating chambers, a lower air pre-heating chamber at each opposite side of said middle wall, a side-by-side pair of common mixing, combustion and delivery conduits each communicating with one of said pre-heating chambers and with one of the main heating chambers at each side of said middle wall, said conduits extending continuously from the main heating chambers to opposite inner end walls of the pre-heating chambers, means for supplying an upward circulation of air through the pre-heating chamber at one side of the middle wall and for exhaust circulation

- tion through and from the heating chamber at the other side of said wall, and fuel supply pipes leading through the inner end wall in to the common mixing, combustion and delivery conduit remote from the heating chamber and substantially above the air pre-heating chamber, all of said pre-heating chambers, common delivery conduits and supply pipes being arranged on opposite sides of the middle vertical wall, the delivery conduits communicating with the main heating chambers at each side thereof.
14. A furnace having main walls enclosing a pair of main endmost transversely communicating heating chambers, lower air pre-heating chambers separated by a common wall and respectively communicating with the inner portions of the heating chambers at opposite sides thereof for incoming and outgoing circulation on a common horizontal plane, and having continuous incoming and outgoing conduits communicating vertically with all portions of the pre-heating chambers, said conduits being provided with controlling valves for alternating the circulation through said pre-heating chambers for incoming and outgoing circulation therethrough, and means for introducing fuel gas into the said conduits and into the circulation of pre-heated air at points remote from the heating chambers.
15. A furnace having main outer walls enclosing a pair of endmost heating chambers at each side of a middle division wall having a circulation opening therethrough, said division wall having on opposite sides thereof a pair of lower parallel air pre-heating chambers each communicating by a continuous conduit with the inner portion of that heating chamber upon the corresponding side of said division wall for incoming and outgoing horizontal circulation through the heating chambers, said conduits extending above the entire area of the pre-heating chambers, conduits serving alternatively for air supply and fuel exhaust respectively communicating with the lower portions of the pre-heating chambers and having controlling valves for reversing the circulation, and means for introducing fuel into each conduit at a point remote from the main heating chamber.
16. In a furnace having main walls enclosing endmost main heating chambers separated by a middle transversely open dividing wall, and side-by-side lower vertically circulating air preheating checkerwork chambers in duplicate arrangement, said middle vertical wall having on opposite sides thereof upwardly extending mixing chambers communicating respectively with said checkerwork chambers, mixing chambers between the main heating chambers and each of said checkerwork chambers extending above the checkerwork chambers approx- imately half the depth and full length of said chambers, means for introducing an independent supply of fuel to each of said mixing chambers above the checkerwork chambers at a point remote from the main heating chambers, and means for alternately supplying air to one of said checkerwork chambers and withdrawing waste gases from the other.
17. A furnace as in claim 16 having the mentioned fuel introducing means in the form of a gas supply above the checkerwork and remote from the main heating chambers and also characterized by the inclusion within the lower portion of each checker-work chamber of means for introducing fuel gas thereto for upward circulation through the checkerwork chamber into the mixing chamber.
18. A furnace as in claim 16 having the as mentioned fuel introducing means in the form of a gas supply above the checkerwork and remote from the main heating chamber and also characterized by the inclusion within the lower portion of each checkerwork chamber of an enclosed supplemental chamber communicating downwardly with the air supply and upwardly through the checkerwork, and a gas supply pipe leading into said supplemental chamber.
19. In combination, a pair of side-by-side transversely communicating soaking pits, means for admitting a combustible mixture into one pit thereof consisting of a longitudinal mixing chamber, means for supplying fuel gas to the outer end of the mixing chamber, means below the mixing chamber and gas supply therefor for pre-heating air in its flow towards the mixing chamber, said chamber being of the full length and extending beyond the air pre-heating means to the soaking pit, means controlling air supply to the air pre-heating means, and a mixing chamber leading from the opposite soaking pit having similar fuel supply means and lower air pre-heating means adapted to also provide for outgoing circulation of waste gases.
20. In combination, a pair of side-by-side transversely communicating soaking pits, means for admitting a combustible mixture into one pit thereof consisting of a longitudinal mixing chamber, means for supplying fuel gas to the outer end of the mixing chamber, means below the mixing chamber and gas supply therefor for pre-heating air in its flow towards the mixing chamber, said chamber being of the full length and extending beyond the air pre-heating means to the soaking pit, means controlling air supply to the air pre-heating means, a mixing chamber leading from the opposite soaking pit having similar fuel supply means and lower air pre-heating means adapted to also provide for outgoing circulation of waste gases,

and means for controlling the supply of air to the pre-heating means and the exhaust of waste gases therefrom respectively.

21. A furnace having main walls enclosing two transversely communicating heating chambers, a mixing chamber leading to one of the heating chambers, an air pre-heating chamber communicating with the mixing chamber and with an outer air supply, the mixing chamber being of the full length and extending beyond the air pre-heating chamber to one of the main heating chambers, air circulating checkerwork in the pre-heating chamber, a fuel supply at the outer end of the mixing chamber, a return circulation chamber like the mixing chamber leading off from the opposite main heating chamber and having a similar fuel supply, a waste gas chamber like the air pre-heating chamber communicating with the mixing chamber and with a waste gas outlet, gas circulating checkerwork like the air circulating checkerwork in the waste gas chamber, means controlling inflow of air to the air pre-heating chamber, and means controlling outflow of waste gases from the waste gas chamber.

22. A furnace as in claim 21 characterized by means supplying gas for upward flow through the checkerwork for combination with air in the mixing chamber.

23. In a furnace, the combination with plural soaking pits, of enclosing side and end walls and a longitudinal division wall with a transverse opening located inwardly from the outer end walls and extending from the end walls between the soaking pits and rearwardly therefrom providing an uppermost chamber leading into one soaking pit and an uppermost chamber leading from the other soaking pit at the opposite side of said division wall, means supplying fuel through the inner end walls to each of said uppermost chambers, a regenerator below each of said chambers, means supplying both fuel and air to each of said regenerators, and means controlling supply of air to one regenerator and withdrawal of waste gases from the other, whereby the flame travel through the soaking pits is alternatively reversed at intervals.

24. A reversible regenerative heating furnace having a pair of regenerators and two main soaking pit chambers separated by a dividing wall having an opening therethrough, air and gas passages leading thereto and therefrom through the regenerators, and circulation control means for said passages whereby both air and gas are pre-heated in a single regenerator and whereby said regenerator on reversal serves as an outlet conductor for waste gases.

25. In a furnace, main outer walls enclosing two main transversely communicating heating chambers and corresponding lower vertically circulating air pre-heating chambers

having regenerative checkerwork therein and an upper mixing portion communicating with the corresponding heating chamber, means for alternately supplying air to one of said chambers while withdrawing waste gases from the other; and means for introducing fuel gas to the lower portion of each chamber for upward circulation through the checkerwork therein.

26. In a furnace, main outer walls enclosing two main transversely communicating heating chambers and corresponding lower vertically circulating air pre-heating chambers having regenerative checkerwork therein and an upper mixing portion communicating with the corresponding heating chamber, means for alternately supplying air to one of said chambers while withdrawing waste gases from the other; an enclosed supplemental chamber in the lower portion of each checkerwork chamber communicating downwardly with the air supply and upwardly through the checkerwork, and a fuel supply pipe leading into said supplemental chamber.

In testimony whereof we hereunto affix our signatures.

GEORGE NAISMITH.
DONALD M. NAISMITH.
